FEED SCREW RELEASING MEANS

Landon R. Gray, Manhattan Beach, and Harry P. Smith, Jr., Los Angeles, Calif., assignors to Richard Seifried, Playa del Rey, Calif.

Application November 1, 1951, Serial No. 254,284

8 Claims. (Cl. 74—424.8)

1

This invention relates to means for releasing a lead screw from operative engagement with a member that is brought to adjusted position by said lead screw. The present invention is a continuation-in-part of our pending application, Serial No. 182,928, filed September 2, 1950.

While the present invention may be used in other connections, it is particularly adapted to be used in stretch-forming machines where opposed devices, on opposite ends of a base, are employed to pull on the ends of a work-piece, while simultaneously forming said work-piece over a die. Considerable pull is, thereby, exerted on said devices and, in order that they may retain their adjusted positions on the base during the stretch-forming operation, they are affixed to the base as by keys or the like. Said pulling devices are usually quite large and too heavy to be manually moved to adjusted position, and for this purpose, power driven lead screws are used for effecting longitudinal traverse of each said device to a desired position on the base.

Assuming that a key is used to interlock each pulling device and the machine base, it will be realized that such a key, in order to fit its keyways in the base and pulling device, must be sufficiently undersize of the keyways to permit of introduction and removal as adjustment is made. Accordingly, while the keys hold the devices fixed on the base for all practical purposes, there is slight movement of the devices toward each other that is absorbed when the stretch-forming operation is instituted. Such a movement would create a stress on the lead screws where the same are engaged with the pulling devices and may cause the threads of said screws to break or to become so fatigued that rapid deterioration would result.

Accordingly, it is an object of the present invention to provide novel and improved means for releasing a feed or adjusting member from forces that are applied to a device that is fed or adjusted by said member so that said forces may be taken only by means provided for such purpose.

Another object of the invention is to provide means as above indicated that entails movement or retraction of an element relative to the feed or adjusting member, and carried by the device, to a position in which the forces on the device are ineffective on the feed or adjusting member.

Another object of the invention is to provide, in means of the character indicated, a nut for the feed or adjusting member having operative engagement with the device, said nut being mov-

2

able relative to both the device and the feed and adjusting member to release the latter from forces tending to move the device.

5 A further object of the invention is to provide, in means as indicated, an element that interferes with the insertion of means for taking the thrust or force on said device unless the nut is moved to release the feed or adjusting member from such thrust or force, thereby assuring such release.

10 The invention also has for its objects to provide such means that are positive in operation, convenient in use, easily installed in a working position and easily disconnected therefrom, economical of manufacture, relatively simple, and of general superiority and serviceability.

15 The invention also comprises novel details of construction and novel combinations and arrangements of parts, which will more fully appear in the course of the following description. However, the drawings merely show and the following description merely describes embodiments of the present invention, which are given by way of illustration or example only.

20 In the drawings, like reference characters designate similar parts in the several views.

Fig. 1 is a front elevational view of an arm of a stretch-forming machine showing a preferred form of the present invention applied thereto.

25 Fig. 2 is an enlarged detail view, partly in section, showing the present means in the position of the parts at the end of the adjustment movement.

30 Fig. 3 is a similar view showing the operative position wherein the feed or adjusting member is released from the force of a stretch-forming operation.

35 Fig. 4 is a vertical sectional view as taken on line 4—4 of Fig. 3.

40 Fig. 5 is a view similar to Fig. 3 of a modification, the scale being enlarged.

Fig. 6 is a vertical sectional view as taken on line 6—6 of Fig. 5.

45 Fig. 7 is a fragmentary end sectional view comparable to Fig. 6, showing a position similar to the position of Fig. 2.

The arm 10, while movable in a horizontal plane relative to a fixed base (not shown), constitutes a base on which is mounted a tension cylinder assembly 11. The latter comprises a bracket 12, a pressure fluid cylinder 13 pivotally mounted on said bracket as on a pivot 14, said cylinder having a piston therein, and said piston having a piston rod 15 extending from one end of the cylinder and carrying a chuck or the like 16.

50 In practice, assembly 11 is positioned along the

3

top 11 of arm 10 according to the length of a work-piece 18 clamped in chuck 16 and which is to be formed and stretched by retraction of piston rod 15 and of a similar opposed piston rod on a similar assembly 11 carried by a similar arm 10, all in opposition to the arm and assembly shown in Fig. 1. In the present case, a strong key 19 is employed to lock the adjusted position of assembly 11 on arm 10, said key being engaged in a keyway 20 provided in the base of bracket 12 and in a selected keyway of a series of keyways 21 provided in arm top 17.

It will be clear that admission of fluid to each cylinder 13 of the opposed assemblies 11 and in the ends thereof that cause retraction of rods 15, will pull the chucks 16 apart and exert a stretch force on work-piece 18. Consequently, the brackets 12 are pulled toward each other by such force and said pull is resisted by keys 19. Since said keys are slightly under-size of the keyways, they fit in order to be readily inserted and removed when adjustment of assemblies 11 is desired, the first result of a stretch-forming pull is a slight movement of brackets 12 toward each other. When the keys take hold, such movement stops and, for all practical purposes, the brackets 12 are firmly affixed to arms 10 during a stretch-forming operation.

In the present case, a lead screw 22, mounted between bearings 23 and 24 on arm 10, constitutes the means for adjusting assembly 12 along top 17. The power for rotating the screw comprises an electric motor 25 and a reducing gear 26 interconnecting the motor and the screw for relatively slow rotation of the latter. Motor 25 is of the reversing type so that the screw may be rotated in either direction, as desired.

According to the invention, means 27 is provided to operatively interengage bracket 12 of assembly 11 and feed screw 22. In Figs. 1 to 4, said means 27 comprises a bracket 28 affixed to bracket 12 and having spaced depending walls 29 apertured at 30 to freely pass screw 22. A plate 31 connects the free ends of walls 28 to render them rigid. A nut 32 is engaged with screw 22 and resides in the space between bracket walls 29, the width of the nut being substantially less than the space between walls 29, thereby allowing for traverse of the nut from positions abutted against either wall 29 to a position intermediate and spaced from said walls. The nut is held against rotation by sliding engagement with plate 31.

In practice, bracket 28 is vertically aligned with keyway 20 so that nut 32 is substantially centered on said keyway when in the mentioned intermediate position. An upstanding plate member 33 is secured to said nut and the upper end of said member is formed with a bifurcation 34 somewhat larger than the lower portion of keyway 20 and in register therewith only when the nut 32 is in said intermediate position.

Fig. 3 shows the normal position in which the bracket 12 is subject to pull relative to base arm 10. When it is desired to change the position of said bracket and assembly 11 to another part of said arm, key 19 is pulled through bifurcation 34. Motor 25 is started to rotate screw 22 in a direction to move assembly 11 to the left or right as desired. The first rotation of the screw will move nut 32 into abutment with one wall 29 and continued rotation will cause the nut to move bracket 28 and assembly 11 until keyway 20 aligns with that keyway 21 that is selected for the new position. This new position is shown in Fig. 2 and it will be noted that not only is the nut still

5 abutted against wall 29, but bifurcation 34 is out of register with keyway 20. Therefore, it is not possible to re-insert key 19 to lock assembly 11 to arm 10. By rotating feed screw 22 in the opposite direction to bring nut 32 to the intermediate position of Fig. 3, said keyway 20 and bifurcation 34 are re-aligned and key 19 may be slid into place.

10 In the above manner, assurance is had that the thrust on bracket 12 cannot be transmitted to nut 32 to cause mutilation or other damage to the threads of screw 22. Thus, the purposes of the invention are accomplished by releasing the screw from the forces or thrust on bracket 12 that seek to move said bracket along arm 10. Key 19 alone, or comparable locking means, serves to absorb such thrust.

15 In Figs. 5 to 7, means 27 comprises a bracket 35 affixed to bracket 12 and having spaced depending walls 36 in which bearings 37 freely pass feed screw 22. Front and back plates 38 connect said walls to render them rigid. In this case, a half nut 39 is disposed between walls 36 and the width of said half nut is substantially less than 20 the space between said walls.

25 Half nut 39 is mounted below feed screw 22 and is held against rotation by guiding engagement with walls 38. An eccentric cam 40 extends between walls 38 and is carried by a pin 41 extending through and between said walls. A pair of straps 42, trained around cam 40 and having their ends connected to the half nut, operatively connect said half nut to said cam, the connection being a sliding one as well as one that moves the half nut toward and away from screw 22 when said cam is rotated on pin 41. An elongated handle 43, terminating in a knob 44, is provided for manipulating cam 40.

30 Fig. 5 corresponds to Fig. 3 and is the normal position in which bracket 12 is subject to pull relative to base arm 10. It will be clear that, after key 19 is pulled and screw 22 started rotating, handle 43 is pulled up as in Fig. 7, to cause cam 40 to push the half nut 39 into engagement with the rotating feed screw. Here also, the nut first slides into abutment with one wall 36 and then pushes against said wall to effect traversing movement of bracket 12 and assembly 11 carried thereby. When register of keyway 20 is achieved with 35 a selective keyway 21 on base arm 10, handle 43 is released or pushed down, causing straps 42 to pull the half nut free of screw 22. Said screw may continue to rotate until stopped but key 19 may now be slid into place with assurance that the half nut, while still abutting one wall 36, cannot transmit the thrust on bracket 12 to the threads of screw 22.

40 While the invention that has been illustrated and described is now regarded as the preferred embodiments, the constructions are, of course, subject to modifications without departing from the spirit and scope of the invention. It is therefore not desired to restrict the invention to the particular forms of construction illustrated and described, but to cover all modifications that may fall within the scope of the appended claims.

45 Having thus described the invention, what is claimed and desired to be secured by Letters Patent is:

50 1. In a structure having a base provided with a plurality of keyways and having a member provided with a keyway adapted to register with a selected one of said plurality of keyways and said registered keyways being receptive of a key 55 to lock the member to the base against a thrust

on the member, a feed device carried by the base, an element engaged with the feed device and movable therewith, a pair of abutments secured to the member, one on each side of the element, and spaced apart a distance greater than the length of said element, the element, during movement by the feed device, first abutting one of said pair of abutments and then moving said abutment and the member along the base to effect the mentioned register of keyways, said element being subject to the thrust on said member when abutting said abutment, and means to move said element to release the same from the force of said thrust.

2. In a structure according to claim 1: the feed device comprising a lead screw and the element engaged therewith comprising a non-rotational nut movable by rotation of said lead screw.

3. In a structure according to claim 1: the feed device comprising a lead screw and the element engaged therewith comprising a non-rotational nut movable by rotation of said lead screw, and the means to move said nut element to release position comprising motive power to rotate the lead screw in a direction to move said nut element to a position spaced from and intermediate the pair of walls.

4. In a structure according to claim 1: the feed device comprising a lead screw and the element engaged therewith comprising a non-rotational nut movable by rotation of said lead screw, and the means to move the nut element to release position comprising a manually operable eccentric cam carried by said pair of walls and rotationally and slidably connected to the nut element.

5. In a structure having a base provided with a plurality of keyways and having a member provided with a keyway adapted to register with a selected one of said plurality of keyways and said registered keyways being receptive of a key to lock the member to the base against a thrust on the member, a lead screw carried by the base, a nut engaged with the lead screw and movable therewith, a pair of abutments secured to the member, one on each side of the nut, and spaced apart a distance greater than the length of the nut, the nut, during rotation of the lead screw, first abutting one abutment of said pair of abutments and then moving said abutment and the member along the base to effect the mentioned register of keyways, said nut being subject to the thrust on said member when abutting said abutment and, thereby, subjecting the threads of the lead screw to said thrust, and motive power to means to rotate the lead screw in a direction to back the nut away from the abutment which abuts to a position where the same is released from said thrust.

6. In a structure according to claim 5: an element fixed to the nut and movable therewith, said element being provided with a bifurcation in register with the keyway in the device only when the nut is in the backed off position.

7. In a structure having a base provided with a plurality of keyways and having a member provided with a keyway adapted to register with a selected one of said plurality of keyways and said registered keyways being receptive of a key to lock the member to the base against a thrust on the member, a lead screw carried by the base, a pair of spaced abutments secured to the member and through which the lead screw extends, a manually operable eccentric cam carried by said pair of abutments and in spaced relation to the lead screw, and a half nut disposed between said pair of abutments and connected to the eccentric cam, slidably relative thereto, and movable by said cam into and out of engagement with the lead screw, said half nut, when moved by the cam to a position disengaged from the lead screw, releasing said lead screw from the thrust on the member.

8. In a structure having a base provided with a plurality of keyways and having a member provided with a keyway adapted to register with a selected one of said plurality of keyways and said registered keyways being receptive of a key to lock the member to the base against a thrust on the member, a lead screw carried by the base, a pair of spaced abutments secured to the member and through which the lead screw extends, a manually operable eccentric cam carried by said pair of abutments and in spaced relation to the lead screw, and a half nut disposed between said pair of abutments and connected to the eccentric cam, slidably relative thereto, and movable by said cam into and out of engagement with the lead screw, the pair of abutments being spaced apart a distance greater than the length of the half nut, said half nut, when moved to engaging position with the lead screw first being moved by the latter to abut one of said pair of abutments and then moving said abutment and members to effect the mentioned register of keyways, said half nut being subject to the thrust on said member when abutting said abutment and, thereby, subjecting the threads of the lead screw to said thrust, said half nut, upon movement by the cam to a position separated from the lead screw, releasing the latter from the thrust on the member.
